OSCAR ^{INVENTOR.}
HAUGE

BY Lindell Johnson
ATTORNEY

UNITED STATES PATENT OFFICE.

OSCAR HAUGE, OF SAN MATEO, CALIFORNIA.

DESIGN FOR A PASTRY CONTAINER.

Application filed October 17, 1928. Serial No. 28,523. Term of patent 14 years.

To all whom it may concern:

Be it known that I, OSCAR HAUGE, a citizen of the United States, residing in the city of San Mateo, county of San Mateo, State of California, have invented a new, original, and ornamental Design for Pastry Container, of which the following is a specification, reference being had to the accompanying drawing, forming a part thereof.

I claim:

The ornamental design for a pastry container as shown.

OSCAR HAUGE.
